UNITED STATES PATENT OFFICE.

RAYMOND SOCKS AND FRANK P. SMITH, OF SHELBYVILLE, INDIANA.

WIRE-STRETCHER CLAMP.

SPECIFICATION forming part of Letters Patent No. 736,453, dated August 18, 1903.

Application filed June 18, 1902. Serial No. 112,231. (No model.)

To all whom it may concern:

Be it known that we, RAYMOND SOCKS and FRANK P. SMITH, citizens of the United States, residing at Shelbyville, in the county of 5 Shelby and State of Indiana, have invented a new and useful Wire-Stretcher Clamp, of which the following is a specification.

This invention is an improvement in wire-stretchers, and has for its object to improve 10 the construction of wire-stretcher clamps to provide a simple and inexpensive device by which the wire may be readily stretched to the required tension and which will hold the wire in convenient position for attachment to 15 the post or other support.

Other novel features of the device will appear in the annexed description and be specified in the claim following.

In the drawings illustrating the invention, 20 Figure 1 is a side elevation viewed from the front or wire-entering side, and Fig. 2 is a similar view from the rear side. Fig. 3 is a plan view.

The device consists in two opposing jaw 25 members 10 11, the member 10 rigidly secured, as by rivets 10^a 10^b, to a base-plate 12, and the member 11 pivotally secured at 11^a in the same base-plate, as shown. The base-plate 12 is wider at the point where the jaw 30 member 10 is attached than at the point where the jaw member 11 is pivoted, and the narrow side of the base-plate is extended and bent over the jaw member 11 at 12^a and adapted to support the outer end of the pivot 35 11^a, as shown. The opposing faces of the jaw members are reversely curved, as shown at 13 13^a, respectively, and are extended rearwardly and provided with links 14 14^a, the links united by a ring 15.

Attached to the rear face of the base-plate 40 12 is a spring 16, extending rearwardly and engaging the pivoted jaw member 11 by an offset 16^a, as shown. The spring is preferably connected to the head 12 at 16^b and supported by a pin 16^c, as shown in Fig. 2. The spring exerts its force to maintain the jaws in constant engagement, so that when the wire is first inserted between the curved portions 13 13^a it will be held with sufficient 45 force to obviate the necessity for holding the jaws closed upon the wire by hand while ad-

justing the draft means to the ring 15. This is an important feature of the invention and saves much valuable time in applying the device to the wire.

The construction of the base-plate 12 with the wide base portion to which the rigid member 10 is connected and the extended overlapping portion 12^a, forming a support for the movable jaw member 11, is also an important 55 feature of the invention and greatly strengthens and supports the connection, so that a much greater tension can be applied to the wire without danger of breaking the jaw members or straining the parts. This produces a very simple, cheap, easily-applied, and very strong device, which is readily applicable to all the various purposes for which similar devices are usually employed. The parts can be of any desired size to adapt 60 them to different-sized wire.

Having thus fully described our invention, what we claim is—

In a wire-stretcher, the combination with a base-plate having a laterally-extended finger 75 folded backward upon itself to form an extended lateral recess, a movable jaw member pivoted at its forward end in the recess between the overlapping finger and base-plate, a fixed jaw member rigidly connected at its 80 front end to the base-plate, said jaw members being extended rearward from the base-plate in substantially parallel relation and having their active faces curved throughout their entire length in opposite directions, whereby 85 they are adapted for clamping wires varying widely in size, a pair of links connected one with each of the jaw members at its rear end, an attaching member carried by the link, and a spring attached to the rear face of the base-plate and extending rearwardly therefrom with its free end bearing upon the rear end of the movable jaw member and tending to 90 normally hold the same in clamping position.

In testimony that we claim the foregoing as 95 our own we have hereto affixed our signatures in the presence of two witnesses.

RAYMOND SOCKS.
FRANK P. SMITH.
